Patented Apr. 4, 1916.

UNITED STATES PATENT OFFICE.

CHARLES W. FINGER, OF DETROIT, MICHIGAN, ASSIGNOR OF ONE-HALF TO CHARLES R. MUELLER, JR., OF DETROIT, MICHIGAN.

MACHINE FOR BENDING STEREOTYPE-MATRICES.

1,178,443.

Specification of Letters Patent.

Patented Apr. 4, 1916.

Application filed October 21, 1915. Serial No. 57,050.

To all whom it may concern:

Be it known that I, CHARLES W. FINGER, a citizen of the United States, residing at Detroit, in the county of Wayne and State 5 of Michigan, have invented a new and useful Machine for Bending Stereotype-Matrices, of which the following is a specification.

This invention consists in means for rolling a stereotype matrix into semi-cylindrical 10 or tubular form so that it can be readily inserted into the stereotype casting machine, and the object of the invention is to provide a machine which shall bend the matrix evenly throughout its width, thus avoiding 15 the breaking or cracking of the face of the matrix and the loosening of the packing usually employed to support high spots.

After the type have been set and locked 20 into flat forms, sheets of moist matrix paper are placed over the type and pressed down against them, usually by means of a proper roller. The sheets are then baked in order to harden them and to fix the impressions. The matrices must next be bent to cylindrical 25 form so that cylindrical sleeves of stereotype metal may be cast, which castings are then machined to fit the cylinders of the presses. These matrices are usually bent by hand, often by pulling them across an edge 30 of a work bench, which results in numerous breaks or cracks with unevenly bent portions of the matrix between them. This results in the exterior surface of the stereotype cylinders being slightly uneven and 35 results in uneven printing.

In the accompanying drawing Figure 1 is a rear elevation and Fig. 2 is a side elevation of a machine embodying my invention. Fig. 3 is a detail of the driving clutch.

40 Similar reference characters refer to like parts throughout the several views.

The machine shown in the drawing has two sides 1 and 2 of a frame, formed with bearings 3 for the shaft 4 of the upper roll 45 5, and with slots 6 for the bearings 7 of the shaft 8 of the lower roll 9. The bearings 7 rest on coil springs 10 mounted in proper pockets in the frame, and these springs rest on small plates 12 supported by adjusting 50 screws 13.

The upper roll is generally in the form of a spiral to avoid the jog or offset that would occur at the line where the matrix overlaps, and adjacent the shoulder 14 are secured 55 two sheets 15 and 16 of strong, tough elastic

material such as rubber cloth or pulp board, two sheets 17 and 18 of thin flexible sheet metal, and a small spacing strip 19 which acts as a stop or gage for the end of the matrix, all secured in position by screws 20. 60 A table 21 of any desired construction may be connected to the frame.

The upper roll is turned by means of the crank 22. In order to prevent reverse rotation of this roll by means of the crank when 65 a matrix is between the rolls, a roller clutch of any well known construction is installed between the crank 22 and a collar 23 secured on the shaft 4. This collar has the usual notches 24 that receive the short rollers or 70 balls 25, the sleeve 26 on the crank serving as the other member of the clutch. A collar 27 on the shaft 4 prevents the crank from slipping off the end of the shaft.

When a matrix 29 is to be bent, the pad 15 75 and sheet 17 of metal are laid back over the roll 5 and onto a cross bar and the matrix 29 is placed on the sheet 18 and pad 16, after which the sheet 17 and pad 15 are laid onto the matrix, as shown in Fig. 2. The roller 5 80 is then turned to the right until the matrix, the metal sheets and the pads are all tightly wound onto this roller, the lower roller 9 being tightly pressed against the matrix to insure even engagement and bending. After 85 the matrix has been entirely wound on the roller, it is pulled back, turning the rollers in the reverse direction, until the parts are again as shown in Fig. 2. It will be understood that the roller 5 is preferably of less 90 diameter than the interior diameter of the finished stereotype sleeve.

The advantage of the four sheets 15, 16, 95 17 and 18 is as follows: By having sheets of metal in direct contact with the matrix, any narrow grooves or other depressions in either side of the matrix will be bridged so that the matrix virtually becomes a sheet with smooth sides. But sometimes the matrix is not of even thickness throughout, that 100 is, it may have spots of slightly greater or less thickness than the balance of the sheet, which will cause the sheet metal to bulge at these points. The softer pads between these metal sheets and the rollers may be compressed slightly more by such increases in thickness of the materials between them, while at the same time transfer to the remainder of the sheet sufficient pressure to cause it to bend evenly. 105 110

The side frames 1 and 2 may be spaced by means of sleeves 31 and held together by means of bolts 32. Brackets 33 and 34 on the frame may be formed with slots 35 to receive the bearings 36 of the shaft 37 of the auxiliary pressure roller 38. This roller is smaller in diameter than the roller 9 and greatly assists in the proper bending of the matrix. It is held against the roller 5 by means of the springs 39 that are properly tensioned by means of the screws 40 and the small plates 41. It will be understood that the thickness of the webs 15 and 16, the sheets 17 and 18 and the spacing strip 19 is the same as the height of the shoulder 14 so that there will be no sudden shocks at the edge of this shoulder as the rollers 9 and 38 pass over it.

It has been found that the roll 5 should be smaller in diameter than the roll on which the sleeve of stereotype metal is to be mounted.

I claim:—

1. In a machine for bending stereotype matrices, the combination of a pair of rolls, one above the other, bearings for said rolls, means to press the rolls against each other, the lower roll being cylindrical and the upper being substantially spiral in cross section and thus formed with a longitudinal shoulder, and retaining devices for the matrix secured to said upper roll and consisting of two sheets of rubber cloth and two thin sheets of metal between them.
2. In a machine for bending stereotype matrices, the combination of a frame, a roll mounted in said frame and formed with a longitudinal shoulder, the surface of said roller being of substantially uniform curvature from the top around to the bottom of said shoulder, retaining devices for the matrix secured to said roll and consisting of two sheets of flexible elastic material and two thin sheets of metal between them, means to hold the metal sheets separated at the line of attachment to the roll, a second roll mounted in the frame, means to press said rolls against each other, and means to turn the rolls.
3. In a machine for bending stereotype

matrices, the combination of a frame, three rolls journaled therein, means to press two of the rolls against the third, and matrix-retaining means secured to the third roll consisting of two sheets of compressible material and two sheets of incompressible material between them, the matrix being placed between the sheets of incompressible material and wound upon the roll to which said sheets are attached.

4. In a machine for bending stereotype matrices, the combination of a frame, three rolls journaled therein, means to press two of the rolls against the third, matrix-retaining means secured to the third roll consisting of two sheets of compressible material and two sheets of incompressible material between them, the matrix being placed between the sheets of incompressible material and wound upon the roll to which said sheets are attached, and means to revolve said rolls.

5. In a machine for bending stereotype matrices, the combination of a frame, a pair of rolls journaled therein, means to press one of the rolls against the other, matrix retaining means secured to one of the rolls consisting of two sheets of compressible material and two sheets of incompressible material between them, the matrix being placed between the sheets of incompressible material and wound upon the roll to which said sheets are attached, a crank, and a clutch between the handle and one of the rolls whereby the crank may turn the rolls when turned in one direction but will be ineffective when turned in the other direction.

6. In a machine for bending stereotype matrices, the combination of a pair of rolls, bearings for said rolls, means to press the rolls against each other, and retaining devices for the matrix secured to one of the rolls and consisting of two sheets of elastic material and two thin sheets of metal between them.

In testimony whereof I sign this specification.

CHARLES W. FINGER.
